(57) **CLAIM**

The ornamental design for a communications apparatus for sensor with optical communication function, as shown and described.

DESCRIPTION

FIG. 1 is a perspective view of the top, front and right side of a communications apparatus for sensor with optical communication function showing our new design; FIG. 2 is a perspective view of the top, rear and left side thereof;

FIG. 3 is a top plan view thereof;

FIG. 4 is a front view thereof;

FIG. 5 is a right side view thereof;

FIG. 6 is a left side view thereof;

FIG. 7 is a rear view thereof; and,

FIG. 8 is a bottom view thereof.
